UNITED STATES PATENT OFFICE.

LUTHER K. JEWETT, OF BOSTON, MASSACHUSETTS.

PASSENGER-CAR TRUCK.

SPECIFICATION forming part of Letters Patent No. 388,046, dated August 21, 1883.

Application filed October 7, 1887. Serial No. 251,705. (No model.)

To all whom it may concern:

Be it known that I, LUTHER K. JEWETT, of Boston, county of Suffolk, and State of Massachusetts, have invented an Improvement in Passenger-Car Trucks, of which the following description, in connection with the accompanying drawings, is a specification, like letters on the drawings representing like parts.

This invention relates to that class of car-trucks shown and described in United States Patents Nos. 361,845 and 361,846, dated April 26, 1887, wherein a metallic bolster is fitted and adapted to move vertically in a metallic transom.

In the car-truck shown in the patents referred to the bolster is supported upon spiral springs which rest upon a seat sustained by links. The links referred to embrace a rocker-bar on a saddle supported by an arch-bar in the case of a swing-motion truck, as shown in Patent No. 361,846, or the said links embrace the saddle itself in the case of a rigid truck, as shown in Patent No. 361,845. In car-trucks having the construction shown in the patents referred to it is necessary to employ spiral springs, and it is one of the objects of this invention to so construct the trucks that elliptical springs may be used to sustain the load of the car. In accordance with my invention this is accomplished by constructing the saddle, as will be described, whereby the links sustaining the spring-seats, either in the rigid or swing-motion truck, are removed from over the arch-bar and carried in toward the center of the truck for a sufficient distance to permit elliptical springs to be employed without having the ends thereof project from the truck beyond the limit allowed.

Another feature of my invention consists in providing each half of the center plate through which the king-bolt is extended with one or more circular grooves, with which to co-operate balls to reduce the friction on the center plate to a minimum, the said balls lying in the grooves of the center plate attached to the bolster, and being embraced by the grooves in the center plate attached to the rocker. To further diminish the friction between the car-truck and the car-body, the curved plate supported by the bolster is also provided with one or more grooves to receive balls, which are engaged or embraced by grooves in the curved

plate attached to the rocker, this latter construction particularly diminishing the friction when the car travels around a curve of the track.

Another feature of my invention consists in rigidly uniting the car-truck to the car-body, as will be described, so that in case of collision the car-trucks will not readily be parted from the car-body, thus diminishing the danger of the telescoping of cars.

Other features of my invention will be pointed out in the claims at the end of this specification.

Figure 1 is a side elevation of a passenger-car truck embodying my invention; Fig. 2, a section of Fig. 1 on line *x* *x*. Fig. 3 is a plan view of one-fourth of the car-truck detached from the car-body; Fig. 4, a sectional detail on line *y* *y*, Fig. 2, to clearly show the manner of securing the car-truck to the car-body; and Fig. 5 a sectional detail, the section being taken on line *y*' *y*', Fig. 4.

Referring to Fig. 1, I have shown my improvements as applied to a swing-motion passenger-car truck of the class referred to, and more particularly the most of the truck shown is substantially such as represented and described in another application, Serial No. 236,551, filed by me April 29, 1887, wherein the wheels *a* *a*, axles *a*' *a*', and housings 3 are as usual in passenger-car trucks.

The arch-bar *a*', its sustaining blocks or castings *a*⁴, the equalizer-bar *a*⁵, and springs *a*⁶, supporting the blocks *a*', the pedestals *a*⁷, and the truss *a*⁸ are all substantially as in the patent referred to.

The transom *a*⁹, herein shown as made in one piece, is riveted to the arch-bar sustaining blocks or castings *a*⁴, and has co-operating with it the bolster *a*¹⁰, supported above the said transom by the links *a*¹², substantially as shown in United States Patent No. 361,846.

Each link *a*¹² supports a spring seat, *b*², sustaining one or more elliptical springs, *b*³, the said spring-seats *b*² at opposite sides of the truck, as herein shown, being pivotally connected by a rod, *b*⁴. The links *a*¹², as herein shown, embrace a rocker-bar, *b*⁵, resting and adapted to rock upon a bar, *b*⁶, forming one part of my improved saddle. The bar *b*⁶ is connected to a second bar, *b*⁷, by cross-bars *b*⁸, only one of which is shown in Fig. 3, the bar *b*⁷

resting upon and being supported by the arch-bar a^3 . (See Fig. 2.) The bar b^6 , as herein shown, rests upon and is secured by bolts b^9 to a channel-bar, b^{10} , extended across and above the bolster, the said channel-bar being fastened to braces b^{12} , extended on opposite sides of and under the transom and riveted thereto, the said bolts b^9 , as herein shown, being extended through that part of the brace b^{12} passing beneath the transom.

My improved saddle in practice will preferably be cast in one piece, and the braces b^{12} will preferably be made separate; but they may be cast integral with the arch-bar sustaining-blocks. It will thus be seen that the bar b^6 , which supports the links sustaining the elliptical springs b^3 , is not supported by the arch-bar a^3 , but is removed therefrom and brought toward the center of the truck for such distance that the elliptical springs will project but little beyond the side of the truck within the limits allowed by railway construction. In a rigid truck, wherein it is desired to employ elliptical springs, the rocker-bar b^5 will be dispensed with and the bar b^6 may be embraced by and sustain the links a^{12} .

Referring to Fig. 2, the lower part, c , of the center plate, secured to the bolster by suitable bolts, as c' , is provided, as shown, with two circular grooves, c^2 c^3 , preferably of unequal depth, the said grooves receiving within them a number of balls, c^4 , which support the upper part, c^5 , of the center plate, secured to the rocker c^x , attached to the car-body, the said upper part, c^5 , being grooved annularly, as shown in Fig. 2, to receive the annular flanges of the part c , two of the annular flanges of the part c^5 being grooved, as at c^6 , to rest upon and partially embrace the said balls c^4 , the annular grooves c^4 being of such depth and the ball therein of such diameter as to enable the upper part, c^5 , of the center plate to be supported entirely by the said balls, thereby obviating friction between the lower face of the upper part, c^5 , and the upper face of the part c . It will thus be seen that when the car travels around a curve the friction between the upper and lower part of the center plate, which in car-trucks of ordinary construction is very great, is reduced to a minimum.

To still further reduce the friction between the car-body and the car-truck and thereby increase easy riding of the car, the upper part, d , of the curved plate secured to the bolster is provided with one or more grooves to secure balls d^2 , the part d being fitted upon the part d of the said curved plate and resting upon springs d^2 located therein, substantially as in United States Patent No. 324,383, dated August 18, 1885. The balls d^2 are preferably about one inch in diameter, and are fitted into grooves in the curved plate d^3 , fastened to the rocker c^x , the said balls raising the curved plate d^3 up out of contact with the part d .

To rigidly secure the car-truck to the car-body and thereby prevent danger of telescoping

ing in case of collision, I have shown a bar, e , extended across and under the transom a^9 , (see Figs. 2 and 4,) the said bar being secured thereto by a nut, e' , on the king-bolte e^2 , extended through the said bar. The bar e is secured, as shown, by bolts e^3 to braces e^4 , one on each side of the transom, (see Fig. 4,) each brace being shown as forked at its end, as at e^6 , (see Fig. 5,) and secured by bolts e^7 to the car-sills e^8 . The bolts e^3 are shown as extended through a guide shown as a sleeve, e^{10} , (see Fig. 4,) and are secured at their upper ends to short trusses e^{12} by nuts e^{13} . The sills e^8 , located at the center of the car, as shown in Fig. 5, are rabbeted to receive the king-bolt sustaining-block e^{14} .

To add increased strength to the truck, the tie-bars forming the pedestals a^1 are made of two pieces, $f f'$, of channel-bar steel, the bar f being fitted into the bar f' , as shown in Fig. 2. It will thus be seen that the danger of telescoping of the car in case of collision, largely caused by the car-body becoming separated from the car-truck, they being loosely held together, as now commonly constructed, by the king-bolt, is diminished to a considerable degree by the rigid connection above described, and the crippling of the car-truck due to the bending of the pedestal tie-bar, is largely obviated by the tie-bar constructed as described.

The curved plates, as herein shown, are located between the arch-bars and the curved plate; but, if desired, the bolster a^{10} may be extended beyond the arch-bar and the curved plates supported at or near the extreme ends of the said bolster beyond the said arch-bars; or, if desired, two curved plates may be employed on each side of the center plate, one on each side of the arch-bar, the curved plate, supported at or near the end of the bolster, being provided with friction-balls.

I claim—

1. In a car-truck, a transom, arch-bars, a bolster, and elliptical springs to support the said bolster, and links to sustain the said springs, combined with a saddle-bar to be embraced by and support the said links away from and within the arch-bars and with a support for the said saddle-bar, substantially as described.

2. In a car-truck, a transom, a^9 , arch-bars and links, a bolster, a^{10} , and elliptical springs to support the said bolster, combined with a saddle-bar comprising the bars b^6 b^7 , and with a support for the bar b^6 within the arch-bar, the bar b^7 being supported by the arch-bar, substantially as described.

3. In a car-truck, a center plate comprising two parts, each provided with one or more annular grooves, combined with balls c^4 , fitted loosely into the said grooves in contact with each other and adapted to sustain the center load of the car, the said balls being free to move in said grooves, substantially as described.

4. In a car-truck, the upper curved plate, d^3 , provided with a groove in its lower face, the lower curved plate comprising the spring-sup-

ported part d' , having a groove in its upper face, and the part d , combined with balls d^2 , fitted into said grooves and adapted to receive part of the load, substantially as and for the purpose specified.

5. The combination, with a car-truck having a transom, a^9 , of a bar, e , extended across and under said transom, and braces e^4 , to rigidly fasten the car-truck to the car-body, substantially as described.

6. The combination, with a car-truck having a transom, a^9 , of a bar, e , extended across and under said transom, and braces e^4 , to rigidly fasten the car-truck to the car-body, and

bolts e^3 , and trusses e^{12} , substantially as described.

7. In a car-truck, the pedestals a^7 , combined with the pedestal tie-bar composed of the channel-bars $f f'$, the channel-bar f being fitted into the channel-bar f' , as and for the purpose specified.

In testimony whereof I have signed my name to this specification in the presence of two subscribing witnesses.

LUTHER K. JEWETT.
